DESIGN FOR A FRUIT SQUEEZER

Jan Kasprzak, New York, N. Y.

Application January 27, 1947, Serial No. 136,451

Term of patent 3½ years

(Cl. D44—29)

To all whom it may concern:

Be it known that I, Jan Kasprzak, a citizen of Poland, residing at New York, in the county of Queens and State of New York, have invented a new, original, and ornamental Design for Fruit Squeezers, of which the following is a specification, reference being had to the accompanying drawing, forming part thereof.

In the drawing:

Fig. 1 is an elevational view of the fruit squeezer showing my new design;

Fig. 2 is a perspective view of the same in a closed position; and

Fig. 3 is the same in an open position.

I claim:

The ornamental design for a fruit squeezer, as shown.

JAN KASPRZAK.
